STRIPPING ROLL FOR LONG FIBER FEEDERS

William F. Bokum, Jenkintown, Pa., assignor to Proctor & Schwartz, Incorporated, Philadelphia, Pa., a corporation of Pennsylvania

Application October 1, 1942, Serial No. 460,442

2 Claims. (Cl. 19—79)

This invention relates to apparatus for feeding fibrous stock to garnett, carding and other fiber-working machines. The present invention relates more particularly to devices for handling relatively long fibers such as sisal, ixtle, tampico, jute, flax, etc.

Fibrous stock is normally fed to carding and garnett machines by what is commonly known in the art as a "weighing feeder." These feeders include a hopper, into which the stock is deposited intermittently by an attendant. Stock is removed from the hopper, in a more or less continuous web, by a spike apron of the endless belt type, with one run of the apron moving upwardly at a steep incline, in one hand of the hopper, and against which the bulk of stock in the hopper is caused to bear.

The apron passes over an upper guide roll by which its direction of movement is reversed. Adjacent the upper end of the descending run of the apron, the feeder is provided with a wiping or stripping cylinder which rotates at a peripheral speed higher than the surface speed of the spike apron.

The stripping cylinder is provided with rigidly mounted teeth which wipe the fibrous stock off the spikes on the descending run of the apron, delivering the stock into the scale pan of the weighing device which forms a part of the feeder.

The scale pan, in turn, intermittently drops weighed batches of the fibrous stock onto the feeding apron of the carding or garnett machine, as is well known in the art.

In handling the longer fibers difficulty has been encountered in clearing the fibers off the rigidly mounted teeth of the stripping cylinder, which frequently results in the fibers becoming wound about the cylinder and necessitating the shutting down of the unit until the cylinder can be cleaned by hand. This entails a loss of time and production.

The object of the present invention is to provide a self-clearing stripping cylinder for wiping long fibers off the spike aprons of automatic weighing feeders and other fiber handling apparatus.

In the accompanying drawings:

Fig. 1 is a sectional elevation, in phantom, of an automatic weighing feeder provided with a self-clearing stripping cylinder constructed and operated in accordance with the principles of the present invention;

Fig. 2 is an enlarged end view, partly in section, of the stripping cylinder shown in Fig. 1;

Fig. 3 is a longitudinal sectional view of the

stripping cylinder as taken on the line 3—3, Fig. 2;

Fig. 4 is a transverse sectional elevation taken on the line 4—4, Fig. 3;

Fig. 5 is a transverse sectional view taken on the line 5—5, Fig. 3; and

Figs. 6 and 7 are detached perspective views of a detail of the invention.

The weighing feeder shown in Fig. 1 is of the type shown and described in the present assignee's prior Patent No. 1,660,249, dated February 21, 1928, to William F. Bokum, the present petitioner, modified in accordance with the copending application of the aforesaid William F. Bokum and John W. Weber, Serial No. 427,668, filed January 21, 1942.

As shown in Fig. 1, the weighing feeder includes a hopper A, with a movable bottom a; a spike apron B, having an ascending run b¹ and a descending run b²; a vertically oscillating evener comb C; a scale pan D; and a delivery conveyor E, which may constitute the feeding apron of a carding or garnett machine or which may deliver the weighed batches of fibrous stock onto the feeding apron of such machine.

The weighing feeder also includes the stripping cylinder 10 which constitutes the subject matter of the present invention.

The stripping cylinder 10 is mounted on a shaft 11, which in turn, is rotatably mounted at each of its opposite ends in a self aligning bearing 12, preferably of the self lubricating or oilless type. Each bearing 12 includes a sleeve 13 having a spherical center 14 mounted for universal movement in a socket bearing 15 which is rigidly secured to a suitable rigid portion 16 of the framework of the feeder.

At each of its ends, and intermediate its ends if desired, the stripping cylinder 10 is provided with a head 17. Each head 17 includes a central hub 18, secured to the shaft 11, and an annular peripheral flange 19 to which latter the outer barrel or shell portion 20 of the cylinder is secured.

Each of the cylinder heads 17 is provided with a plurality of substantially radiating guide slots 21, 21. In the present instance these guide slots are formed in planes tangent to a common circle 30 concentric to the axis of the shaft 11 and hub 18, although it will be understood that the guide slots 21, 21 may be strictly radially disposed with respect to the axis of the shaft 11, if desired.

The guide slots 21, 21 of the various heads 17 are aligned one with another longitudinally of

the cylinder 10, for the reception of a series of retractable and extendable stripping bars 22, 22.

Each of the stripping bars 22 is provided with a series of stripping pins or teeth 23, 23, which are spaced apart longitudinally of and rigidly secured in said bars, said pins being provided with sharply pointed outer ends which are adapted to be projected and retracted through apertures 24, 24 formed in the outer shell or barrel 20 of the cylinder 10.

As shown more particularly in Fig. 4, diametrically opposite pin bars 22, 22, are rigidly connected in the form of a rigid frame by tie yokes 25, 25, whereby, as the pins on one side of the cylinder 10 are projected to wipe the fibrous stock off the spikes of the spike apron, the pins on the opposite side of the cylinder are retracted, causing the portions of the shell 20 which surround the pin holes 24 to wipe off any fibers which may have a tendency to cling to the pins.

In order to effect the outward projection and the inward retraction of the pins 23, each pin bar 22 is provided, at each of its opposite ends, with a slide 26, canted at an angle to the plane of the bar, as shown in Fig. 2. Each slide 26 is slidably mounted in a guideway 27 formed on the outside of an eccentric strap ring 28.

The eccentric strap rings 28, at the opposite ends respectively of the cylinder 10, are rotatably mounted on fixed eccentrics 29. Each eccentric 29 is provided with a neck 30 which encircles the shaft 11, with operating clearance therebetween. Each neck 30 is provided with a flange 31 which is adjustably clamped against the rear face of the adjacent bearing block 15 for the shaft 11, as clearly shown in Figs. 3 and 5.

As shown in Fig. 5, the flanges 31 for the eccentrics 29, are provided with a series of concentric elongated segmental slots 32 for the reception of cap screws 33, 33, tapped into the bearing blocks 15.

By adjusting the eccentrics 29 about the axis of the shaft 11, the point of retraction for the pins 23 may be accurately determined for causing the fibers to drop freely into the scale pan of the weighing feeder.

The opposite ends of the cylinder 10 are respectively closed by discs 34 which are secured to the end heads 17 by screws 35 tapped into bosses 36 formed on the heads 17. The peripheral edges of the discs 34 are preferably seated in annular shouldered recesses 37 formed in the flanges 19 of the end heads 17.

The outer shell or barrel 20 is formed of segmental plates 38, 38, having adjacent edges overlapping, as shown at 39 in Fig. 2, with countersunk screws 40, 40 passing through said overlap joints and tapped into the flanges 19 of the heads 11, whereby a substantially smooth cylindrical surface is presented to the fibers, to discourage any tendency of the fibers to adhere to small protuberances on the shell.

From the foregoing description, it will be clear that as the cylinder 10 is rotated, from any suitable source of power applied to the shaft 11, as through a pulley 41 thereon, at a rate of speed slightly in excess of the surface speed of the spike apron, the pin-teeth 23 will be projected beyond the shell 20, as each set of pins approaches the descending portion of the apron, and will be retracted as the pin bars 22 successively approach the under side of the cylinder 10 by the slides 26 riding in the guideways 27 and the eccentric

straps 28 revolving about the fixed eccentrics 29, and with the diametrically opposite pin bars 22, 22 tied together by the yokes 25 to keep the slides, guides and eccentric straps at all times in free cooperating relation to each other.

By adjusting the eccentrics 29 about the shaft 11, the point of retraction of the pins 23 and the consequent dropping of the fibrous stock off the cylinder 10 into the scale pan of the feeder may be accurately controlled.

As shown in Figs. 1, 2, and 4, the rows of pins 23 are respectively arranged with the axes of the pins of each row in a plane tangent to a common circle concentric to the axis of rotation of the shell of the stripping cylinder 10, which causes the pins, when projected beyond the peripheral surface of said shell, to be disposed at acute angles to those portions of the shell surface immediately adjacent and preceding the respective rows of pins in the direction of rotation of the shell, whereby the pins assume the form of hooks for more efficiently gripping the fibers.

As shown in Figs. 2 and 4, the pins are retracted by being moved axially in the above noted planes which eliminates the possibility of the fibers being pinched between the pins and the shell surface during such retraction of the pins, whereby the fibers are fully released and dropped clear of the cylinder without clinging thereto and without breaking the fibers.

I claim:

1. A rotary stripping cylinder for fiber handling apparatus, comprising a shell, a shaft coaxial with said shell, heads spaced along said shaft within said shell, a series of pin bars paralleling said shaft and slidably mounted for lateral movement relative thereto in guides formed in said heads in planes tangent to a common circle concentric to the axis of rotation of the shell, a series of pins spaced along each bar, an eccentric encircling said shaft at each end of said cylinder, an eccentric strap encircling each eccentric, a slide on each end of each bar, and a guideway on each eccentric strap for each slide for effecting projection and retraction of said pins through openings in said shell upon relative rotation between said cylinder and said eccentrics, each pin when projected being disposed at an acute angle to that portion of the surface of the shell preceding the pin in the direction of rotation of the shell.

2. A rotary stripping cylinder for fiber handling apparatus, comprising a shell, a shaft coaxial with said shell, heads spaced along said shaft within said shell, a series of pin bars paralleling said shaft and slidably mounted for lateral movement relative thereto in guides formed in said heads in planes tangent to a common circle concentric to the axis of rotation of the shell, a series of pins spaced along each bar, an eccentric encircling said shaft at each end of said cylinder, an eccentric strap encircling each eccentric, a slide on each end of each bar, a guideway on each eccentric strap for each slide, and yokes connecting diametrically opposite pairs of said bars for effecting projection and retraction of said pins through openings in said shell upon relative rotation between said cylinder and said eccentrics, each pin when projected being disposed at an acute angle to that portion of the surface of the shell preceding the pin in the direction of rotation of the shell.

WILLIAM F. BOKUM.
